PROCESS AND APPARATUS FOR STACKING OR STORING DELICATE THIN WEBS OF MATERIAL

This invention relates to a process and apparatus for stacking or storing delicate thin webs of material, e.g. those of cellulose or plastic film, which are taken over at a tensile stress acting continuously from the lower plies of the web of material through the individual plies to the top ply.

It is known to wind webs of material of all kinds onto a core, reel, drum or the like. Insofar as materials such as paper or fabric are concerned, the circular type of winding presents minor difficulties since these webs generally can be wound tightly and thus are not damaged. Completely different, however, is the situation in winding delicate thin webs of material, e.g. in the form of plastic films of a few μ . In this case it is not easily possible to produce a tight stable supporting winding construction.

In accordance with the invention, a process is provided in which a web of material is stacked to give a rotatably mounted stack and, at least at three places, is contacted over its entire width, the value of the contact pressure being limited by a resilient effect of the contact areas, and the speed and tension differences of the web of material occurring when it passes the contact areas are compensated by a movable support which it contacts before impinging on the stack.

Suitable webs of material for stacking or storing according to the process of the invention are delicate thin cellulose or plastic sheet materials which may be surface-treated or coated.

Delicate webs of material of such thickness are stacked which usually are subjected to distortion or pleat formation or the like when being wound onto cylindrical winding rolls.

It has proved advantageous that the width of the web of material to be stacked or stored corresponds at least to the height of the stack. Exceeding the stack height, the width may have any value so that any delicate thin web of material from a production machine can be stacked according to the process of the invention.

The process of the invention for stacking or storing differs distinctly from a winding-up process since it clearly differs from the conditions of the latter process by the present freedom that the material is not forced to yield to the interior.

The number of the contact areas substantially depends upon the dimension of the support and is limited only in that a polygonal form is maintained also after completing the process. A conversion into the circular form must be avoided since then all disadvantages of circular winding would again become apparent.

The number of the contact areas is at least three or more, but it would be particularly suitable to stack on supports with 4 to 12 contact areas. In the case of a support diameter of 200 mm., 6 contact areas are used, for example. The number of the contact areas also depends on the height of the stack since with increasing height the polygonal shape of the stack of the invention approaches more and more a circular shape, which should be avoided. The greater the number of the contact areas, the lower the height of the stack must be, and vice versa.

According to the process of the invention, the web of material is contacted over its entire width since, otherwise, folds, creases or a moving down of the web cannot be avoided.

The contact areas are resilient and may be mounted on the support or may be a part of the support. The contact areas alone form the contact lines for the stack to be supported.

By means of the specific resiliency of the contact areas, which is adapted to the delicacy of the web of material, the load of the individual plies above the contact areas in the closed structure of the stack of the invention is limited exactly to the desired extent, which may be pointed out by the relation contact pressure = counterpressure. This means that when the counterpressure beginning at the contact areas has a certain value on the lower plies in the direction of the stack surface, the contact pressure cannot be higher at any place in the stack.

Stacking or storing according to the process of the invention necessarily leads to speed variations. A substantial feature of the process is to absorb or compensate these variations before the web of material impinges. This is achieved in that, before the stacking or storing operation, the compensating function is transferred to a movable support by a movement in the sense of shortening the web of material. The tension differences in the web of material to be stacked are thus also considerably avoided.

10 The present invention also provides an apparatus for the performance of the process for stacking or storing delicate thin webs of material, which are taken over at a tensile stress acting from the lower plies of the web of material through the individual plies upon the upper one.

15 Referring to the drawings:

FIG. 1 is a schematic view in elevation of one embodiment of the apparatus of the invention, and

FIGS. 2-5 are perspective views of supports employed in the apparatus of the invention.

20 For placing a stack 2 on a dimensionally stable support 1, at least three ribs 4 of a resilient structure or with a resilient indentable sure surface are provided for the entire width of the web of material 5 and, for compensating the speed and tension differences of the web of material 5, a roller 6 is provided which executes an oscillating movement.

25 There are at least three ribs 4 so that, in elevation, the web of material is stacked in the form of a triangle. Stacking or storing of the web of material 5 also may be performed in any other polygonal form as long as no circular cross section is formed. It has proved advantageous that the width of the web of material to be stacked or stored corresponds at least to the height of the stack.

30 Any material having a resilient structure may be employed for the ribs 4, e.g. rubber sponge, soft rubber, elastic hollow sections or structures including air cells. It is also possible to use a material having a resilient surface, e.g. stamped or bent or deep-drawn metal or plastic sections.

35 In a preferred embodiment, the ribs 4 having a resilient structure are provided, in the contact areas with the web of material 5, with a dimensionally stable surface 7, e.g. of metal or synthetic plastic. Care should be taken to ensure a sufficient distance of the dimensionally stable surface 7 from the support 1 so that the resilient indentability of the ribs 4 is not impaired. It is thus avoided that, when mounting the beginning of the web of material 5, nonuniform drawing causes concentrated indentations in the ribs.

40 The ribs 4 mounted on the support 1 may have any cross section, e.g. a circular, semicircular, angular or oval cross section. It is also possible to form the ribs 4 as hollow sections or as hollow sections with an adjustable pneumatic internal pressure. The cross section of the support 1 may have any basic form, but preferably it has a circular cross section.

45 The operation of the roller 6 is as follows: in its nonoperating position and without the action of the mean web tension of the material concerned—with avoidance of too low or too high a tension—the swinging arms 8 forming the connection between the pivot 9 and the center of gravity 12 of the roller would lie in a vertical plane due to the influence of the force of gravity.

50 At the beginning of the stacking procedure, a slight web tension in the direction, and having the value, of the resultant force R resulting from the lateral forces in the web material 55 will already deflect the roller 6 from its vertically suspended position and pivot it in a range resulting from the speed variations of the web of material 5.

55 The tension differences in the web of material 5 also are simultaneously compensated or at least suppressed to such an extent that the stack formation cannot be impaired by stress concentrations in the web of material 5. The weight of the roller 6 advantageously has such a value that the forces available for deflection are sufficient to overcome the acceleration and retardation forces opposed to the roller movement because of the mass moment of inertia.

It has proved advantageous to provide a vertical distance of a few centimeters between the roller 6 and the stack 2 and to maintain it approximately constant. This entails the advantage that the conditions during stacking, particularly the distance of the free web of material 5, remain constant. Direct contact of the stack 2 with the roller 6 would be disadvantageous because of the prompt mechanical influence of the stack 2.

The distance may be provided by advancing the axis 13 or, in the case of a stationary position of the axle 11 of the stack 2, may be provided by changing the pivot 9 of the roller 6 or by other known means. Advancing may be performed manually or automatically by means of known scanning devices, e.g. light barriers, switches with scanning rolls, and the like.

In the case of a relatively thin layer thickness of stack 2 or in the case of a suitable web of material 5, it also is possible to dispense with the advancing movement and to provide a sufficient distance at the beginning.

The apparatus of the invention also may be employed when, before the web of material 5 is transferred to the stack 2, a stationary guide roller is mounted and the speed and tension differences resulting during the formation of the stack are compensated at another place which, however, is in the effective range of the web of material 5. This may be performed also with known methods other than those described here, according to which longitudinal oscillations in the web are to be neutralized.

The tensile stress is so adjusted that the ribs 4 yield only few millimeters. It must be adapted to the characteristics of the web of material to be stored or stacked and normally exhibits decreasing values with an increasing stack height.

The advantages achieved with the invention reside particularly in the fact that, in the predominant part of the stack, the web of material 5, apart from its own weight, is pressure-free stacked in the form of individual plies and practically speaking cannot be damaged, and that, in the area of the ribs 4, the pressure between the individual plies is only slightly above their own weight. As experience has shown, the web of material also is not damaged in these latter areas.

Even in the case of incorrect employment of the process of the invention by too great a tensile stress during stacking of the upper plies of the stack 2, the lower plies may freely sink downward between the individual ribs 4; but the pressure in the contact range does not reach a value above that predetermined by the elasticity of the ribs 4.

Further substantial advantages reside in the fact that the air layer first taken along during stacking is immediately displaced to the pressure-free zone of the stack 2 and can slowly pass from there outward to the front side, whereas in the carrying range above the ribs 4 an almost direct contact is obtained between the individual plies. The good surface adhesion produced therewith considerably limits the possibility of a relative displacement of the plies to one another, which may be initiated by the continuous transfer of the tensile stress, and this permits operation with a substantially lower tensile stress than in the case of the windings of the prior art without the layers being laterally displaced or the lower layers being additionally pushed away downward by loop formation of the upper layers, despite which a transportable and storable stress-free stack is formed and delicate thin webs of material are protected to a particularly high extent. On the other hand, lateral discs or lateral supports, such as are employed in the case of reels, and which usually would interfere with subsequent processing of the stack are advantageously eliminated.

As shown in FIG. 1, a web of material 5 is conveyed over a roller 10 to a stack 2 and stacked there. Conveying the web of material 5 over the ribs 4 and the continuous ply on the stack 2 results in different distances with respect to the axle 11, causing corresponding speed differences which are compensated by a roller 6 movable in the swinging arms 8. A condition is thus provided for the trouble-free stacking of the succeeding layers on the stack 2. The stack 2 is formed by rotating the support 1 about the axle 11.

The vertical distance between the roller 6 and the stack 2 is limited to a few centimeters and can be maintained approximately constant by advancing the axle 11 about the axis 13. Advancing is performed manually or automatically by known scanning devices, not illustrated. It also is possible to perform the advancing movement at the pivot 9 of the roller 6.

Supporting of the stack 2 is performed substantially indirectly by the support 1 which, in this case, has six semicircular ribs 4 which are positioned transversely to the stack direction over the entire width of the web of material. The ribs 4 have a resilient structure or have resilient indentable surfaces.

The ribs 4 are mounted on the support 1; they also may be a part of the support 1.

FIGS. 2, 3, 4, and 5 show some embodiments of the ribs 4 which, for example, are mounted on a cylindrical support 1. In FIG. 2, dimensionally stable surfaces 7 of metal or synthetic plastic are adapted to and mounted on the resilient ribs 4 where the web of material to be stacked contacts the ribs and, furthermore, the dimensionally stable surface 7 is sufficiently distanced from the support 1 so that the resilient indentability of the ribs is not impaired. FIG. 3 shows ribs 4' of a resilient structure with full profile consisting, for example, of rubber sponge, which are mounted on the support 1. FIG. 4 shows an oval 4" and FIG. 5 a round resilient hollow section 4"". Both types of profiles are filled with a predetermined air pressure and thus can be better adapted to the use concerned, after the ends are sealed. Furthermore, there are numerous possibilities for the formation of the ribs 4 and the support 1. A substantial feature of the invention is that, around a rigid support, a number of preferably resilient ribs 4 are arranged which cause exactly defined pressure conditions at the contact areas of the stack. The degree of elasticity, if required, may have an upper value very close to that of a rigid structure.

It will be obvious to those skilled in the art that many modifications may be made within the scope of the present invention without departing from the spirit thereof, and the invention includes all such modifications.

We claim:

1. An apparatus for stacking a delicate thin web of material which comprises rotatable support means having at least three resilient ribs on the surface thereof, the ribs having a length at least equal to the width of the web and a height sufficient to support the stacked web in a polygonal configuration, and a pivotally suspended roller means mounted adjacent to the rotatable support means whereby speed and stress differences of the web occurring when passing over the ribs are compensated by the roller means over which latter the web passes prior to contact with the rotatable support means.

2. An apparatus according to claim 1 in which the ribs are provided with dimensionally stable surfaces.

3. An apparatus according to claim 2 in which the ribs have a circular cross section.

4. An apparatus according to claim 2 in which the ribs have a semicircular cross section.

5. An apparatus according to claim 2 in which the ribs have a angular cross section.

6. An apparatus according to claim 2 in which the ribs have an oval cross section.

7. An apparatus according to claim 2 in which the ribs are hollow.

8. An apparatus according to claim 1 including means for advancing the center of the rotatable support means, whereby a distance of a few centimeters is maintained between material on the support means and the roller means.

9. An apparatus according to claim 1 in which the width of the web is at least equal to the height of the stacked material.

10. A process for stacking a delicate thin web of material which comprises passing the web over a pivotally suspended roller and then onto a rotatable support having at least three resilient areas on the surface thereof in contact with the web and serving to support the stacked web in a polygonal configuration, the speed and stress differences of the web occurring

3,540,669

5

when passing over the resilient areas being compensated by
the roller.

6

11. A process according to claim 10 in which the width of
the web is at least equal to the height of the stacked material.
